CLAIM

The ornamental design for a buckle for luggage strap or
the like, as shown.

DESCRIPTION

FIG. 1 is a front elevational view of a buckle for lug-
gage strap or the like showing my new design;
FIG. 2 is a left side elevational view;
FIG. 3 is a right side elevational view;
FIG. 4 is a bottom plan view thereof;
FIG. 5 is a top plan view thereof; and
FIG. 6 is a rear elevational view.
